Patented Feb. 1, 1921.

INVENTOR
FRANK BRUEGGE MAN
BY *Arthur W. Nelson*
ATTORNEY.

UNITED STATES PATENT OFFICE.

FRANK BRUEGEMAN, OF CHICAGO, ILLINOIS, ASSIGNOR OF ONE-HALF TO JOHN R. RICHARDS, OF CHICAGO, ILLINOIS.

WASHING-MACHINE.

1,367,351.

Specification of Letters Patent.

Patented Feb. 1, 1921.

Application filed May 29, 1920. Serial No. 385,200.

To all whom it may concern:

Be it known that I, FRANK BRUEGEMAN, a citizen of the United States, and a resident of Chicago, county of Cook, and State of Illinois, have invented certain new and useful Improvements in Washing-Machines, of which the following is a specification.

My invention relates generally to improvements in household washing machines, but 10 relates more particularly to power operated washing machines.

The general object of my invention is to provide a washing machine construction that can be used with an ordinary wash tub, *i. e.*, 15 in which a wash tub shall form a part of the complete apparatus.

Another object of my invention is to provide a washing machine construction which shall greatly facilitate the operation of 20 transferring the clothes from the tub in which the clothes are washed to the tub or place of rinsing.

Another object of my invention is to provide a washing machine construction which 25 shall be relatively light in weight, yet of durable form; which shall be low in cost; and which shall generally be adapted to perform the washing operation in a quick, safe, and satisfactory manner.

It is also an object of my invention to provide a washing machine construction, the 30 various parts of which can be quickly and easily assembled and disassembled as required during the washing of several batches 35 of clothes, and as may be necessary for shipping, storing or other periods when the apparatus is not in use.

My invention consists generally in the 40 form, arrangement, construction and coöperation of the parts whereby the above-named objects, together with others that will appear hereinafter, are attainable; and my invention will be more readily understood by reference to the accompanying drawings 45 which illustrate what I consider, at the present time, to be the preferred embodiment thereof.

In said drawings:—

Figure 1, is a view partly in section and 50 partly in elevation of a washing machine construction embodying my invention; and

Fig. 2, is a detail view substantially on the line 2—2 of Fig. 1.

I have shown in the drawings my apparatus 55 as embodying therein a wooden wash

tub 2 but this, it should be understood, is by way of illustration and not by way of limitation for it is obvious that instead of using a wooden tub the usual galvanized iron tub may be used. 60

The tub 2, is a wash tub such as is commonly used wherever the so called stationary washing tubs are not available. For washing purposes it is customary to provide several of these tubs, in one of which the 65 cleansing of the clothes by agitation in soapy water takes place, after which they are transferred, usually by means of a clothes stick, to another tub containing the rinse water. The transferring of the clothes from 70 the tub in which the clothes are washed to the other tub is usually done piece by piece because the water used is generally too hot for the hands. The washing and transferring of clothes by hand in this manner is a 75 slow, laborious and tedious task. At the same time, rubbing the clothes on the wash board, generally used in conjunction with such tubs, results in the rapid destruction of 80 the clothes and particularly of the finer and more delicate pieces. Notwithstanding the many objections inherent in washing clothes in this manner, the great expense and cumbersome character of washing machines heretofore provided has limited their use to 85 those persons who have more than a moderate income, and who have adequate laundry space and facilities.

I have devised a construction which, if desired, can be employed in conjunction with 90 such portable tubs of which the tub 2 is an example and which can be used in a kitchen or other place not provided solely for washing purposes. To this end, I prefer to provide a clothes container which fits within the 95 tub 2. As here shown, this clothes container is composed of upper and lower rings or bands 3, and 4, between which extend a plurality of spaced rods or bars 5. The bars, 5, are preferably of wood although they may 100 be of other material. The ends of the rods 3, it will be observed, are firmly secured in the bands or rings 3 and 4. The bottom of the clothes container is closed by means of a grid 7 which, in the present instance, 105 takes the form of a wire mesh that is suitably secured to the lower ring or band 5 as by means of the clamping ring 8. The clothes container is preferably of a size slightly smaller than the tub so that an inter- 110

vening space 9 is provided. It will be understood that water and soap are placed in the tub 2 and that the clothes to be washed are placed in the clothes container. In order 5 that the clothes may be very quickly, thoroughly and completely cleansed, I provide power mechanism for agitating the clothes. This may assume different forms, but I prefer to provide the simple dolly type of 10 agitating element as indicated at 9. The dolly 9 is suspended on a shaft 10 which shaft is provided with a bevel gear 11 at its upper end. The bevel gear 11, it will be observed, is on the upper side of the base plate 12 15 of the motor 13 so that this prevents the shaft 10 and the dolly from falling. The motor 13, as here shown, is an electric motor preferably provided with electric contacts, as at 14, to which an electric plug can be 20 readily secured and from which it can be very readily removed. The armature shaft 15 is extended outwardly at one end and thereon is secured a worm 16 which in turn meshes with a worm wheel 17 that is journaled on the shaft 18. The shaft 18, in turn, is carried in bearings provided in the casing 19 of the motor. On the shaft 18 I mount a crank or arm 20, which through the medium of the arm 21 and rod 22 is operatively connected to the segment lever 23. The arm 21 is pivotally connected to the lever 23 as at 24, and the lever 23 is pivotally connected to the motor frame or casing as indicated at 25. Thus, it becomes obvious that 30 high speed rotary movement of the motor is converted into relatively low speed swinging or reciprocatory movement in the segment lever 23 by virtue of the worm gearing and the other parts mentioned. The 35 lower end of the lever 23 is provided with a gear rack or segment as indicated at 26 which, in turn, meshes with the bevel gear 11, carried by the shaft 10. Hence, continuous rotation of the motor finally results in driving and reversing the rotary movement of the dolly by which the clothes are thoroughly agitated and quickly cleansed.

As here shown, the motor, gearing, and connected parts are mounted upon a cover 50 member 27 which is of a size sufficient to span the tub, 2. I prefer to dish this cover upwardly in order to give strength and stability thereto and form a rigid support for the motor. If desired, the central part of the 55 cover may be reversely dished or formed as indicated at 28 better to prevent the water from splashing upon the bearing of the shaft 10 and to permit lubrication thereof without danger of getting grease into the water compartment. As here shown, the cover does not 60 rest directly upon the upper edge of the tub 2 but instead rests upon the upper band or ring 3 of the clothes container. The band or ring 3 is provided with an inwardly extending portion 3' and for co-action therewith I

have provided two handle members 29 which carry stem portions free to rotate in the bracket or bearing members 30 that are secured to the cover 27. The lower ends of the handles are provided with extending finger 70 or latch portions 31. Thus when the handles 29 are turned to the position shown in Fig. 1 the fingers or latches 31 engage the underside of the latch or extension 3' of the ring or band 3 and thus firmly secure the cover to the 75 clothes container. Since the clothes container, in operation, is loaded with a batch of clothes the weight thereof will be sufficient to hold it properly in place on the tub 2. In any event, the parts may be fitted sufficiently 80 close to prevent objectionable movement.

After the batch of clothes has been properly washed the handles 29 are turned to free the latch portions 31 from the ring portion 3' at which time the cover and all 85 parts supported thereby, to wit, motor gearing and dolly may be lifted bodily away from the tub and clothes container. Thereafter the entire clothes container, if desired, can be bodily lifted from the tub 2 and carried to the tub containing the rinse water and all of the clothes dumped therein. Of course, if desired, the clothes may be removed from the container to the rinse water in the ordinary manner as by means of 90 clothes stick. So soon as the clothes have been removed a new batch can be placed in the clothes container and the cover member replaced and locked by turning the handles 95 29.

After the washing has been completed the various parts can be easily and quickly disassembled and stored in any convenient place. This feature makes feasible the 100 washing in the kitchen or other place where power washing machines of the type heretofore provided could not be used.

The apparatus which I have designed is light in construction, of durable form, and is one which can be produced at very low 110 cost. Inasmuch as the ordinary wash tub may be used as a part of the apparatus it reduces the total cost of the machine to such a modest sum that it is within the reach of all.

I claim:

1. A washing machine comprising a clothes container adapted to be placed within a wash tub, a cover member adapted to span the wash tub and form a closure therefor and for the clothes container, a clothes agitating element depending from the cover and extending through an opening in the depression thereof, operating mechanism for the agitating element mounted upon the 125 cover and means for detachably connecting said cover and said clothes container.

2. A washing machine construction embodying therein a clothes container adapted to be placed within a wash tub, a ring mem- 130

ber at the upper end of the clothes container and adapted to engage the rim of the tub and to serve as a handle whereby the container may be lifted from the wash tub, a 5 cover member adapted to span the tub and supported on the ring member of the clothes container, operating mechanism supported on the cover and means carried by the cover for detachably engaging the ring member 10 to secure the cover in position.

3. In a washing machine, a tub, a clothes container adapted to be placed within the tub, said clothes container being provided at its upper end with a ring member which 15 engages the rim of the tub, a convexed cover member adapted to span the wash tub and form a closure therefor, an agitator depending from the cover member and extending through an opening in the depression, operating mechanism supported on the 20

cover for actuating the agitator and means carried by the cover for detachably engaging the ring member of the clothes container to secure the cover and its operating mechanism in place. 25

4. In a washing machine, a tub, a clothes container adapted to be placed within the tub, a cover member adapted to span the tub said cover member being convexed upwardly from near its circumference and being reversely dished near the center thereof to form a depression provided with an opening, an agitator shaft depending from the cover and extending through the opening in the depression and operating mechanism 30 supported on the cover over the depression. 35

In testimony whereof, I have hereunto set my hand, this 21st day of May, 1920.

FRANK BRUEGGEMAN.
